LIGHTER MECHANISM

Karl Bernhardt, Vienna, Austria, assignor to
 Louis Vincent Aronson, Newark, N. J.

Application October 8, 1936, Serial No. 104,578
 In Austria December 7, 1935

9 Claims. (Cl. 67—7.1)

This invention relates to lighters such as adapted for lighting cigars and cigarettes. The invention is particularly adaptable to lighters of the type embodying pyrophoric sparking means in conjunction with a wick.

According to this invention the lighter mechanism may be all contained within a compact casing having smooth exterior surfaces and of a size and shape for convenient carrying. Furthermore, the casing is provided with a unique form of closure means operatively associated with the lighter mechanism, whereby upon operation of the latter, a suitable snuffer may be removed from the wick and at the same time a pair of closure members are opened in such manner as to leave space for the snuffer member to protrude and exposing the wick for convenient access. Also the closure members when opened upon operation of the lighter, are so arranged as to temporarily provide wind guards for the flame at the wick and for the shower of sparks directed from the sparking means on to the wick. The closure members when in normal closed position, further serve to supplement the action of the wick snuffer in confining the ignitable vapors, thereby preventing excess evaporation of fuel from the wick and insuring an ignitable vapor mixture in the vicinity of the wick when exposed to the shower of sparks from the sparking means.

Various further objects, features and advantages of the invention will become apparent from the following detailed description, taken in connection with the accompanying drawing which discloses by way of example only, one embodiment of the invention. The invention consists in such novel features, arrangements and combinations of parts as are described in the following specification and shown in the accompanying drawing.

In the drawing, Fig. 1 shows a longitudinal sectional view and a partial elevation of the cigarette lighter in its closed condition;

Fig. 2 represents a sectional view on line 2—2 of Fig. 1;

Fig. 3 shows the cigarette lighter in the same sectional view as Fig. 2 but in its open condition;

Fig. 4 is a horizontal sectional view on the line 4—4 of Fig. 1;

Fig. 5 is a vertical sectional view on the line 5—5 of Fig. 1, in enlarged scale; and

Fig. 6 illustrates a side view of the cigarette lighter in its open condition.

The pressure lever 1 or the like which actuates the friction wheel and in the known manner operates under the action of a spring 2, is provided

with two toothed extensions 3 and 4 (Figs. 1 and 5). The toothed member 3 meshes with the friction wheel driver 5, which is toothed on a part of its periphery and in the known manner engages with the lateral teeth of the friction wheel 7 having its bearing upon the axle 6 in such manner that it is capable of being turned. The second toothed member 4 meshes with the teeth of a disc 8 capable of being turned upon its bearing axle 6 and operating the snuffer cap 10 which covers the wick 9 when in closed position. The snuffer cap 10 is fastened to the free end of a lever having one arm 11 connected rigidly with the disc 8 and another arm 11' arranged upon the axle 6.

The lid of the cigarette lighter is formed by two plain leaves 12 which are quite independent of the snuffer cap 10 and lying close to one another within the top of the casing. The two leaves being each nearly half as large as the top of the casing, serve to shut the cigarette lighter quite fully when in the closed position (Fig. 2). The leaves 12 are provided with lateral lugs 13 pivoted at 14 to the adjacent walls of the casing of the cigarette lighter. The leaves are kept in the closed position by a spring 15 acting against the lugs 13.

When the pressure lever 1 is pressed inward, the friction wheel 7 is turned by the wheel driver 5 which is turned by the toothed member 3. The second toothed member 4 turns the disc 8 and thereby the lever arms 11, 11' together with the snuffer cap 10. The snuffer cap 10 and later the arms 11, 11' of the snuffer cap supporting lever are pushed during the opening movement against the leaves 12 and swing the same against the action of the spring 15, like the leaves of a door, into open position in which the arms of the snuffer cap lever bear against the leaves 12 (Fig. 6) and keep them thus in the opening position. As may be perceived from Fig. 3, the leaves 12 are lying in their open position approximately in the planes of the lateral walls of the casing of the cigarette lighter and are thus acting as wind protection surfaces.

When the pressure lever 1 is released, the snuffer cap 10 returns to closed position. The leaves 12 are released thereby and also swing back automatically into closed position by the action of the spring 15. The performance of the two lid parts as simple plain leaves enables an essential simplification of the construction of the cigarette lighter. The construction also has the advantage that the entire inner arrangement of the cigarette lighter may be substantially enclosed

by the side walls of the casing even when in the open condition.

It will be apparent that the closure members when in open position, provide a pair of elongated wind guard elements at either side of the flame at the wick, and also extending along the path of the shower of sparks from the sparking mechanism, thus insuring effective operation of the device even in windy weather. The positions of the wind guard closure elements as above described, appear to considerably improve the lighting properties of the flame as produced in the device. It will be further noted that when the closure members are in closed position, the entire mechanism is housed in a compact casing from which dirt is effectively excluded and at the same time the casing serves to retain any particles of abraded sparking metal or small quantities of fuel against coming in contact with the user's hands or pocket. Also it will be noted that the device when closed is wholly free from any exposed irregular protuberances which might catch or tear the user's pocket. The arrangement of the closure members is such that they will open freely without any substantial friction and without the application of any force to the finger piece appreciably greater than required for the operation of a lighter not provided with the closure means. In short, a normally wholly enclosed lighter is provided in a simple, durable and inexpensive form without handicapping the operation of the lighter mechanism.

While the invention has been described in detail with respect to a particular preferred example, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

1. A lighter comprising a casing, the upper portion of which is formed with an elongated cross section, pyrophoric sparking means and wick means within said portion of the casing, snuffer means for the wick pivotally mounted adjacent said sparking means and including a snuffer cap supporting arm extending lengthwise of said portion, top closure means comprising a pair of elongated leaves extending longitudinally of said portion and each pivoted respectively on axes extending along the two longer top edges of said casing portion, said two leaves when in closed position acting jointly to close the top of the casing, the path of movement of said arm being substantially along a plane including the line of juncture of said leaves when closed, whereby raising of said arm separates adjacent edges of said leaves and turns the same upwardly and outwardly to open position.

2. In a lighter construction, a casing, closure means therefor comprising a pair of complementary leaves normally positioned side-by-side to form a substantially continuous closure surface with a substantially centrally located line of juncture, means for pivotally mounting said leaves respectively along their edges opposite said line, and lighter mechanism within said casing including an element movable upon operation of the lighter, and into engagement with said leaves at said line of juncture whereby the edges of the leaves at said line are separated and opened outwardly.

3. In a lighter construction, a casing, closure means therefor comprising a pair of complementary leaves normally positioned side-by-side to form a substantially continuous closure surface with a substantially centrally located line of juncture, means for pivotally mounting said leaves respectively along their edges opposite said line, and lighter mechanism within said casing including a snuffer cap operating arm movable substantially along a plane including said line of juncture upon operation of the lighter, and into engagement with said leaves at said line of juncture whereby the edges of the leaves at said line are separated and opened outwardly.

4. In a lighter construction, a casing, closure means therefor comprising a pair of complementary leaves normally positioned side-by-side to form a substantially continuous closure surface with a substantially centrally located line of juncture, means for pivotally mounting said leaves respectively along their edges opposite said line, spring means normally biasing said leaves toward closed position, pyrophoric spark producing mechanism and a wick within the casing beneath said closure, and means operatively associating said mechanism and leaves for separating the adjacent edges of said leaves and opening the same outwardly upon operation of said mechanism, said last named means then also acting to retain said leaves within spaced apart substantially parallel planes to form wind guards for said wick during use of the lighter.

5. In a lighter construction, a casing, closure means therefor comprising a pair of elongated complementary leaves normally positioned side-by-side to form a substantially continuous closure surface with a line of juncture extending lengthwise of the leaves, means for pivotally mounting said leaves respectively along their outer longer edges, a single spring member within said casing normally biasing both of said leaves toward closed position, and lighter mechanism within said casing, and means operatively associating said mechanism and leaves for separating the adjacent edges of said leaves and opening the same outwardly upon operation of said mechanism.

6. In a lighter construction, a casing, closure means therefor comprising a pair of elongated complementary leaves normally positioned side-by-side to form a substantially continuous closure surface with a line of juncture extending lengthwise of the leaves, means for pivotally mounting said leaves respectively along their outer longer edges, lighter mechanism and a wick at spaced points within said casing beneath the closure, a snuffer cap operating arm pivoted in the casing adjacent said mechanism and normally extending toward said wick along said line of juncture, said arm adjacent its pivoted end being of a width substantially as great as the spacing of the pivoted axes of said leaves, whereby when the arm is raised in operation said leaves are engaged thereby and separated and thus opened outwardly and retained during use of the lighter with substantially their maximum possible spacing permitted by the pivotal mountings.

7. A lighter comprising a casing, the upper portion of which is formed with an elongated cross section, pyrophoric sparking means and wick means within said portion of the casing, snuffer means for the wick pivotally mounted adjacent said sparking means and including a snuffer cap supporting arm extending lengthwise of said portion and mounted at one end for

5 pivotal movement for carrying a snuffer cap upwardly at its other end, top closure means comprising a pair of elongated leaves extending longitudinally of said portion and each pivoted respectively on axes extending along the two longer top edges of said casing portion, said two leaves when in closed position acting jointly to close the top of the casing and adapted for movement to open position by separation of the adjacent elongated edges of the leaves outwardly and upwardly, permitting said arm to be raised therebetween.

10 8. In a lighter construction, a casing, closure means therefor comprising a pair of flap-like members, a pair of spaced apart pivotal means for supporting said members respectively whereby when the members are in closed position the edges thereof opposite from said supporting means come together along a line of juncture, and whereby said edges, when the closure is 15 opened, are separated and swing outwardly, pyrophoric spark producing mechanism and a wick within said casing beneath said closure means, a snuffer member in said casing and operatively associated with said mechanism, whereby when

20 25

the lighter is operated said snuffer member is raised between said separated edges of the closure members.

9. In a lighter construction, a casing, a closure means therefor comprising a pair of flap-like members, a pair of spaced apart pivotal means for supporting said members respectively whereby when the members are in closed position, the edges thereof opposite from said supporting means come together along a line of juncture, and whereby said edges when the closure is opened, are separated and swing outwardly, spring means for urging said members toward closed position, pyrophoric spark producing lighter mechanism and a wick within said casing beneath said closure means, said mechanism including an element movable upon operation of the lighter and operatively associated with said members for opening the same, and spring means for returning said element to normal position within the casing after operation of the lighter, permitting said closure members to assume their closed positions.
